(57) **CLAIM**

The ornamental design for a stemmed drinking receptacle holder, as shown and described.

DESCRIPTION

FIG. 1 is a perspective view of the stemmed drinking receptacle holder illustrating my new design;

FIG. 2 is a another perspective view of a the stemmed drinking receptacle holder of FIG. 1;

FIG. 3 is a plan view of the top of the stemmed drinking receptacle holder of FIG. 1;

FIG. 4 is a plan view of the bottom of the stemmed drinking receptacle holder of FIG. 1;

FIG. 5 is an elevation view of the right side of the stemmed drinking receptacle holder of FIG. 1;

FIG. 6 is an elevation view of the left side of the stemmed drinking receptacle holder of FIG. 1;

FIG. 7 is an elevation view of the rearward end of the stemmed drinking receptacle holder of FIG. 1; and,

FIG. 8 is an elevation view of the forward end of the stemmed drinking receptacle holder of FIG. 1.

The broken lines showing a stemmed drinking receptacle in FIG. 1 are included for the purpose of showing an environmental feature that forms no part of the claimed design. The broken lines showing a through-void having an opening that terminates at a right side of the holder in FIGS. 1-5 are included for the purpose showing of portions of the holder that form no part of the claimed design. The broken lines showing a hinge in FIGS. 1, 2 and 5-8 are included for the purpose of showing portions of the holder that form no part of the claimed design.

1 Claim, 5 Drawing Sheets
